ROLAND R. CRUM, OF WHITTIER, CALIFORNIA, ASSIGNOR TO H. C. SMITH MANUFACTURING COMPANY, OF WHITTIER, CALIFORNIA, A CORPORATION OF CALIFORNIA

EXPANSIBLE UNDERREAMER

Application filed October 15, 1928. Serial No. 312,475.

This invention relates to an expandible underreamer having longitudinally extending cavities in its periphery and cutters accommodated therein for longitudinal play and lateral movement to effect expansion and contraction. The present invention appertains particularly to an expansion control means for guiding the cutters and retaining them in their several positions.

10 The objects of this invention are to provide an expandible underreamer of the character described having any or all of the following features:—a catch on one end of a cutter to guide it in and out of lateral expanded and contracted positions; a catch co-operating with a lateral bearing surface to laterally support a cutter in expanded position; a latch longitudinally movable and having a retaining surface to co-operate with a complementary surface on the catch and retain the cutter against lateral displacement from the body; a latch as last specified, which, in its cutter expanded position, projects beyond the periphery of the body of the underreamer 25 so as to be engageable by a casing shoe when the underreamer is “pulled”, and is movable thereby to cause collapse of the cutters.

These objects together with other objects and corresponding accomplishments are obtained by means of the embodiments of my invention illustrated in the accompanying drawings, in which:—

Fig. 1 is an elevation of an underreamer; Figs. 2, 3 and 4 are sections taken on the planes correspondingly indicated in Fig. 1; Fig. 5 is a central longitudinal section through the underreamer with parts in collapsed position, a fragment of the well hole and the lower end of a well casing being shown; and Fig. 6 is a central longitudinal section showing the underreamer parts in expanded position.

Referring with more particularity to the drawing, a well hole is shown with a casing 45 10 having a shoe 11 at the bottom thereof. The underreamer is adapted to be lowered through the casing to a point below the shoe, where it automatically expands. In the embodiment shown herein, the underreamer is 50 illustrated with three cutters, although it

will be obvious that more or less may be used. As the cutters, and their associated parts are of like construction, it will not be necessary to describe more than one. The underreamer has a body substantially of cylindrical shape 55 and marked 12. At the upper end the body is shown provided with a tapered threaded pin 13 for attachment of the tool to a drill string, and at the lower end is provided with a threaded box 14 for attaching the usual drilling tools such as a bit. Extending lengthwise through the body is a circulation passage 15 having communicating water courses to direct the wash to the working parts. In the body are longitudinally extending cavities 16 for the accommodation of cutters. At the bottom of each cavity is a pocket 17 for a follower or a propelling means for its cutter. At the upper end of each cavity is a ramp 9 comprising an inclined surface sloping outwardly and upwardly. In the body and above the ramp is a channel 18 for a latch and providing a lateral supporting surface 19 for its cutter. At the upper end of each channel 70 is a rider or offsetting plate 20 having a bevelled lower face 21. Each channel 18 has longitudinally extending mortises at their sides for receiving corresponding tenons on a latch.

In each cavity at its lower end is fulcrumed 80 a block 22 having a socket to receive the ends of a roller cutter shaft 23. The blocks are fulcrumed to the body by means of pins 24 extending across the cavities and disposed in elongated slots 25 in the block. Each roller cutter shaft as shown is bent and has roller cutters or reamers 26 journaled thereon. Mounted upon the upper end of each shaft 23 is a block or catch 27 having a sloping bearing face 28. The tips of the catches are 85 arranged to be engaged with the ramps 9. The catches have lateral faces 29 for engagement with the supporting faces 19 on the body.

Each pocket 17 has slidably disposed therein a follower 8 housing a compression spring 30, the follower bearing against the lower end of block 22 and urging its cutter longitudinally upward. A lock hole 31 is provided in the cap and a cooperating lock hole 32 in the 90 100

outer wall of the pocket for registration when the spring is completely compressed as shown in Fig. 5. The follower may be locked in compressed position by means of a pin 33 shown in Fig. 5. This pin may be inserted 5 when the underreamer is placed in collapsed position preliminary to insertion in the casing. However, it is removed before the underreamer is lowered.

A latch 34 with dove tails for the mortises 10 is mounted in each channel 18. Each latch has a lower sloping retaining surface 35 complementary to the bearing surface on the catch. An inwardly sloping shoulder 36 is provided on the rear of the latch for cooperation with the ramp. In the construction 15 shown, the latch is urged downwardly by its own weight.

In order to set the cutters in collapsed position, they are moved downwardly against 20 the action of the compression spring 30 and the catches 27 are swung inwardly with their tips at the lower ends of the ramps 9 as shown in Fig. 5. The latches are disposed in their lower position with their shoulders 36 under 25 the ramps 9 and their retaining surfaces 35 engaging the bearing surfaces 28. In this position, the cutters will be retained in collapsed position. However, the latches will be urged upwardly, but held against such 30 movement by the well casing bearing laterally against the latches. When the underreamer passes below the casing shoe 11 with the latches clear thereof, the latter are free 35 to be moved laterally. The compression springs 30 expand pushing the cutters upwardly and causing the tips of the catches to ride outwardly over the ramps 9 to clear the latter. The latches are moved upwardly by 40 the catches riding outwardly by reason of the shoulders 36 and bevelled upon ends 37, so that the latches are projected laterally resting against the riders 20, and the catches bearing against the supporting surfaces 19. 45 The cutters are then retained in expanded position and against displacement as shown in Fig. 6. The tenons on the latches have a lateral clearance in their mortises to permit outward movement and riding of the latches onto the offset plates 20.

50 What I claim is:—

1. In an underreamer, the combination of 55 a body having a longitudinally extending cavity in its periphery with an outwardly sloping ramp at one end, a cutter accommodated in said cavity for longitudinal play therein and having a connection to said body so that it may be moved laterally thereon into and out of expanded position, means tending 60 to move said cutter toward said ramp, a catch secured to said cutter and having an outer lateral bearing surface, the tip of said catch engaging said ramp to cause said cutter to be retracted and projected upon longitudinal movement thereof, and a longitudinally mov- 65

able latch on said body having a retaining surface complementary to and engaging the bearing surface on said catch to prevent outward lateral displacement of said cutter.

2. In an underreamer, the combination of 70 a body having a longitudinally extending cavity in its periphery with an outwardly sloping ramp at one end, a cutter accommodated in said cavity for longitudinal play therein and having a fulcrum connection to said body at one end so that said cutter may be rocked laterally into and out of expanded position, means tending to move said cutter toward said ramp, a catch secured to said cutter and having an outer lateral bearing surface, the tip of said catch engaging said ramp to cause said cutter to be retracted and projected upon longitudinal movement thereof, and a longitudinally movable latch on said body having a retaining surface complementary to and engaging the bearing surface on said catch to prevent outward lateral displacement of said cutter. 75

3. In an underreamer, the combination of 80 a body having a longitudinally extending cavity in its periphery with an outwardly sloping ramp at one end and a lateral support surface beyond said ramp, a cutter accommodated in said cavity for longitudinal play 85 therein and having a connection to said body so that it may be moved laterally thereon into and out of expanded position, means tending to move said cutter toward said ramp, a catch secured to said cutter and having an outer lateral bearing surface, the tip of said catch engaging said ramp to cause said cutter to be retracted and projected and longitudinal movement thereof, said catch in expanded 90 position overlapping and bearing against said support surface, and a longitudinally movable latch on said body having a retaining surface complementary to and engaging the bearing surface on said catch to prevent outward lateral displacement of said cutter. 95

4. In an underreamer, the combination of 100 a body having a longitudinally extending cavity in its periphery with an outwardly sloping ramp at one end and a lateral support surface beyond said ramp, a cutter accommodated in said cavity for longitudinal play 105 therein and having a fulcrum connection to said body at one end so that it may be rocked laterally into and out of expanded position, means tending to move said cutter toward said ramp, a catch secured to said cutter and having an outer lateral bearing surface, the tip of said catch engaging said ramp to cause said cutter to be retracted and projected upon longitudinal movement thereof, said catch in 110 expanded position overlapping and bearing against said support surface, and a longitudinally movable latch on said body having a retaining surface complementary to and engaging the bearing surface on said catch to prevent outward lateral displacement of said cutter. 115

prevent outward lateral displacement of said cutter.

5. In an underreamer, the combination of a body having a longitudinally extending cavity in its periphery with an outwardly upwardly sloping ramp at the upper end, a cutter accommodated in said cavity for longitudinal play therein and having a connection to said body so that it may be moved laterally theron into and out of expanded position, means tending to move said cutter toward said ramp, a catch secured to the upper end of said cutter and having an upwardly inwardly sloping bearing surface, the tip of said catch engaging said ramp to cause said cutter to be retracted and projected upon longitudinal movement thereof, and a longitudinally movable latch on said body having a retaining surface sloping complementary to and engaging the bearing surface on and engaging said catch to prevent outward lateral displacement of said cutter.

25 6. In an underreamer, the combination of a body having a longitudinally extending cavity in its periphery with an outwardly sloping ramp at its upper end, a cutter accommodated in said cavity for longitudinal play therein and having a connection to said body so that it may be moved laterally thereon into

30 7. and out of expanded position, means tending to move said cutter upwardly toward said ramp, a catch secured to said cutter and having an outer lateral bearing surface, the tip of said catch engaging said ramp to cause

35 8. said cutter to be projected upon upward movement thereof into expanded position, and a longitudinally movable latch connected to said body so as to be moved laterally outward on its upward movement and having a retaining surface complementary to and engaging the bearing surface on said catch to prevent outward lateral displacement of said cutter.

40

7. In an underreamer, the combination of
a body having a longitudinally extending cavity
in its periphery with an outwardly sloping ramp at its upper end, a cutter accommodated in said cavity for longitudinal play therein and having a fulcrum connection to said body at its lower end so that said cutter may be rocked laterally into and out of expanded position, means tending to move said cutter toward said ramp, a catch secured to said cutter and having an outer lateral bearing surface, the tip of said catch engaging said ramp to cause said cutter to be projected upon upward movement thereof into expanded position, and a longitudinally movable latch connected to said body so as to be moved laterally outward on upward movement and having a retaining surface complementary to and engaging the bearing surface on said catch to prevent outward lateral displacement of said cutter.

85 8. In an underreamer, the combination of

a body having a longitudinally extending cavity in its periphery with an outwardly sloping ramp at its upper end and a lateral support surface above said ramp, a cutter accommodated in said cavity for longitudinal play therein and having a connection to said body so that it may be moved laterally thereon into and out of expanded position, means tending to move said cutter upward toward said ramp, a catch secured to said cutter and having an outer lateral bearing surface, the tip of said catch engaging said ramp to cause said cutter to be projected upon upward movement thereof into expanded position, said catch in expanded position overlapping and bearing against said support surface, and a longitudinally movable latch connected to said body so as to be moved laterally outward on its upward movement and having a retaining surface complementary to and engaging the bearing surface on said catch to prevent outward lateral displacement of said cutter.

9. In an underreamer, the combination of a body having a longitudinally extending cavity in its periphery with an outwardly sloping ramp at its upper end and a lateral support surface above said ramp, a cutter accommodated in said cavity for longitudinal play therein and having a fulcrum connection to said body at its lower end so that it may be rocked laterally into and out of expanded position, means tending to move said cutter toward said ramp, a catch secured to said cutter and having an outer lateral bearing surface, the tip of said catch engaging said ramp to cause said cutter to be projected upon upward movement thereof into expanded position, said catch in expanded position overlapping and bearing against said support surface, and a longitudinally movable latch connected to said body so as to be moved laterally outward on its upward movement and having a retaining surface complementary to and engaging the bearing surface on said catch to prevent outward lateral displacement of said cutter. 110

10. In an underreamer, the combination of a body having a longitudinally extending cavity in its periphery with an outwardly sloping ramp at its upper end, a cutter accommodated in said cavity for longitudinal play therein and having a connection to said body so that it may be moved laterally thereon into and out of expanded position, means tending to move said cutter upwardly toward said ramp, a catch secured to said cutter and having an outer lateral bearing surface, the tip of said catch engaging said ramp to cause said cutter to be projected upon upward movement thereof into expanded position, and a longitudinally movable latch connected to said body having a retaining surface complementary to and engaging the bearing surface on said catch to prevent outward lateral movement of said cutter. 115

120

125

130

- displacement of said cutter, said latch and said body having engaging bearing surfaces stepped so that said latch will offset laterally outward in upper position and inset in lower position.
- 5 11. In an underreamer, the combination of a body having a longitudinally extending cavity in its periphery with an outwardly sloping ramp at its upper end, a cutter accommodated in said cavity for longitudinal play therein and having a fulcrum connection to said body at its lower end so that said cutter may be rocked laterally into and out of expanded position, means tending to move said cutter toward said ramp, a catch secured 10 to said cutter and having an outer lateral bearing surface, the tip of said catch engaging said ramp to cause said cutter to be projected upon upward movement thereof into expanded position, and a longitudinally movable latch connected to said body having a retaining surface complementary to and engaging the bearing surface on said catch to prevent outward lateral displacement of said cutter, said latch and said body having engaging bearing surfaces stepped so that said latch will be offset laterally outward in upper position and inset in lower position.
- 15 12. In an underreamer, the combination of a body having a longitudinally extending cavity in its periphery with an outwardly sloping ramp at its upper end and a lateral support surface above said ramp, a cutter accommodated in said cavity for longitudinal play therein and having a connection to said body so that it may be moved laterally thereon into and out of expanded position, means tending to move said cutter upward toward said ramp, a catch secured to said cutter and having an outer lateral bearing surface, the tip of said catch engaging said ramp to cause said cutter to be projected upon upward movement thereof into expanded position, said catch in expanded position overlapping and bearing against said support surface, and a longitudinally movable latch connected to said body having a retaining surface complementary to and engaging the bearing surface on said catch to prevent outward lateral displacement of said cutter, said latch and said body having engaging bearing surfaces stepped so that said latch will be offset laterally outward in upper position and inset in lower position.
- 20 13. In an underreamer, the combination of a body having a longitudinally extending cavity in its periphery with an outwardly sloping ramp at its upper end and a lateral support surface above said ramp, a cutter accommodated in said cavity for longitudinal play therein and having a fulcrum connection to said body at its lower end so that it may be rocked laterally into and out of expanded position, means tending to move said cutter toward said ramp, a catch secured to
- said cutter and having an outer lateral bearing surface, the tip of said catch engaging said ramp to cause said cutter to be projected upon upward movement thereof into expanded position, said catch in expanded position overlapping and bearing against said support surface, and a longitudinally movable latch connected to said body having a retaining surface complementary to and engaging the bearing surface on said catch to prevent outward lateral displacement of said cutter, said latch and said body having engaging bearing surfaces stepped so that said latch will be offset laterally outward in upper position and inset in lower position.
- 25 14. An underreamer comprising a body, a cavity in the periphery thereof, an elongated cutter member accommodated in said cavity for longitudinal and lateral play, means to hold one end of said cutter member against lateral displacement in relation to said body, an outwardly offset bearing surface in said cavity for the other end of said cutter member to rest against whereby in one longitudinal position said cutter member rests thereagainst and is disposed in projected position and in the other longitudinal position said cutter member is retracted, a latch on said body longitudinally movable and having a lateral bearing against said other end of said cutter member, said latch and said body having engaging bearing surfaces disposed so that in one longitudinal position of said latch corresponding to the like longitudinal position of said cutter member said latch will be offset laterally outward and hold said cutter member against lateral displacement.
- 30 In witness that I claim the foregoing I have hereunto subscribed my name this 20th day of September, 1928.
- 35 ROLAND R. CRUM.
